FLOOR NAILING MACHINE

Daniel J. Dougherty, Snohomish, Wash., assignor
of forty-nine one hundredths to Oscar A.
Gregorson, Seattle, Wash.

Application August 21, 1945, Serial No. 611,826

6 Claims. (Cl. 1—46)

1

This invention relates to improvements in floor nailing machines, and it has reference more particularly to machines for nailing wood floors that are made of boards without the usual tongue and groove edges and which boards are laid edge to edge and nailed straight through from the top; such flooring usually being of hardwood and comprising boards from one-quarter to one-half inch thick and from one and one-half to three inches wide, and which, preparatory to final nailing, are put in place over the area to be floored, then wedged tightly together and held for final nailing.

It is the principal object of this invention to provide a nail driving machine that will operate automatically, after being initially placed in position and started, to travel across the prepared area, and to quickly and uniformly drive a row of nails; each board receiving a nail therethrough closely adjacent each of its opposite side edges or at designated intervals that best suit the particular floor being laid.

Another object of the invention is to provide for the advancement of the machine by intermittent movements and to effect the driving of the nails during the periods of rest. Furthermore, to provide means for advancing the machine, after each nail is driven, that certain distance required to properly locate it for the next driving operation, whether the advance be relatively long as across a board, or relatively short, as when advancing from the edge of one board to the adjacent edge of the next board.

Still another object of the invention is to provide a machine of the above stated kind that will advance straight across a floor area, and wherein a novel stop device is provided to engage a wall or stopping abutment to actuate the said stop device to release the driving clutch of the machine after the machine has traversed an area, so that it may be reversed and again started across the area.

Still further objects of the invention reside in the details of construction of the various parts, in their combination, and in their relationship and mode of operation as will hereinafter be fully described.

In accomplishing the above mentioned and other objects of the invention, I have provided the improved details of construction, the preferred forms of which are illustrated in the accompanying drawings, wherein—

Fig. 1 is a side view of a floor nailing machine embodied by the present invention.

Fig. 2 is a front elevation of the same.

2

Fig. 3 is a view of that side of the machine opposite the side shown in Fig. 1.

Fig. 4 is a fragmental top view of parts, showing the nail feed channel and the nail release device for dropping the nails, one at a time, for delivery to the hammer or driving mechanism.

Fig. 5 is a view of the parts seen in Fig. 4, showing their position after being actuated for dropping a nail.

Fig. 6 is a detail, in side elevation, particularly of those parts of the mechanism whereby the intermittent and varied advance movements of the machine are effected.

Fig. 7 is a detail of the ball clutch ratchet mechanism used with the devices for advancing the machine across a floor.

Fig. 8 is a longitudinal sectional view of the hammer guide and nail holder.

Fig. 9 is a sectional detail of the nail supply hopper and a part of the nail delivery channel.

Fig. 10 is a detail of the mechanism for actuating the caster truck to lift the machine clear of the floor.

Fig. 11 is a sectional detail of the driving clutch between the motor shaft and driving gears.

Fig. 12 is an upper end view of the nail driving hammer and hammer guide bracket.

Fig. 13 is a sectional detail of the receiving end portion of the nail guide tube and its mounting block.

Fig. 14 is a side view of parts showing the disposition of the nail feed mechanism relative to its actuating means.

The present machine is designed, upon being initially set in place and started, to move under its own power straight across an area on which floor boards have been placed in position for nailing. The travel is effected in a succession of intermittent movements, and a nail is driven after each advancement and while the machine is at rest. Also, provision is made that for the nailing of flooring of the usual widths, the advance movements shall alternately be long and short, so that the nails may be driven through each board close to its opposite edges; the nails that are driven next to the adjacent edges of adjacent boards being relatively closely spaced, and the interval between them is herein referred to as "short," while nails that are driven through the opposite edges of the same board are spaced farther apart, and this is herein referred to as the "long" interval.

Provision is also made that during each advance movement, a nail will be admitted to the nail holder of the driving shoe, the hammer

lifted, and when the advance movement stops, the hammer is forcibly actuated to drive the nail; then there is another advance movement. With each advancement, another nail is dropped and the hammer is reset, and this operation continues until the machine is stopped.

Referring more in detail to the drawings—

The machine, in its present preferred form, comprises a horizontally disposed, rectangular base 10, supported across its forward and rearward ends by parallel rollers 11 and 12 of substantial length. These rollers have trunnions 13 extending from their ends revolvably mounted in bearings 14 that are fixed to the under side of the base 10 adjacent its corners, as noted best in Fig. 3. Preferably, the supporting rollers are equipped with slightly enlarged tires 12' at their ends to better insure straight travel in rolling on a floor that may be slightly uneven.

Mounted rigidly on the base 10 is a vertical bracket 15 which rigidly supports a gear box 16 upon its upper end. Mounted upon the gear box is a nail supply hopper 17 from which the nails for securing the floor are delivered, by means presently described in detail, to the nail holder for driving by the hammer. The hopper is shown to be equipped with a cover 17c that is hingedly attached, as at 18.

The means powering the machine for effecting its travel and the movement of the various parts, comprises an electric motor 20 that is fixed on the base 10 below the gear box 16 and rearwardly of the bracket 15. The motor shaft 21 is axially aligned with a drive shaft 22 that is revolvably mounted in the gear box 16 in bearings 23 and 23. The lower end of shaft 22 may be operatively connected with and released from the motor shaft 21 through the mediacy of a releasable clutch device, indicated generally in Fig. 1 at 24, later more fully described.

On shaft 22, as seen in Fig. 1, is a worm gear 25 which drives a gear 26 that is fixed on a horizontal shaft 27 that extends through and is revolvably mounted in the gear box 16. Fixed on one end of the shaft 27, at the outside of the gear box, is a crank arm 28. On the other end of the shaft, at the outside of the gear box, is a belt pulley 30, best seen in Fig. 3, over which a belt 31 operates to drive a pulley 32 that is fixed on a shaft 33 extending horizontally through the nail picker housing 17.

In Fig. 9, it is noted that the nail picker housing forms a cylindrically shaped enclosure and that the shaft 33 is coaxial thereof. It is also therein noted that the shaft 33 is equipped with short radial arms 34 designed to keep the supply of nails in the housing in a stirred up condition and that there are two arms, designated by reference character 34', longer than the others, having outer end portions adapted to move along a slot 35 in the hopper base. This slot leads upwardly along the forward side of the housing into a downwardly inclined channel or guide slot 38 which is formed between two parallel, slightly spaced bars 39—39' which are best shown in Figs. 4 and 5. The slots 35 and 38 are of such predetermined width that the heads of the nails will not pass through and therefore the nails that are brought into the slot by the action of the arms 34' will be suspended by their heads in the channel, and will form in a row as seen in Figs. 1 and 2. The row of nails held in the downwardly inclined channel 38 will advance by gravity to the lower end thereof and there provision is made whereby they will be individually delivered into the upper

end of a tube 40 that leads downwardly, as noted in Fig. 2, to the hammer guide 41 wherein they are delivered to the nail holder shoe 42 for driving by the hammer.

Referring now more particularly to Figs. 1 and 8, it will be observed that the hammer guide 41 comprises a vertical tubular member terminating at its lower end in a squared block-like portion 41a which is formed as an integral part of the base 10 at a forward side corner thereof. Continuing upwardly from the block 41a is an elongated cylindrical standard 41b. An axial bore 43 is formed the full length of the parts 41a and 41b. The lower face of the block 41a is somewhat above the floor level, as seen in Fig. 6, and the shoe 42, having a rounded under surface to facilitate easy sliding on the floor, is disposed between the block and floor. This shoe has a vertical stem portion 45 slidably contained in the lower end of the bore 43 and formed through the shoe, and its stem is an axial bore 46 that opens upwardly into the bore 43 with a conical flare as at 46'. With the travel of the machine across a floor, the shoe 42 rides on the floor surface and the guide stem 45 moves up or down in the bore 43 as may be required to meet slight surface variations.

The nail delivery tube 40 enters the block 41a above the upper end of the shoe guide stem, as will be noted in Fig. 8, and nails delivered through the tube, will enter point first into channel 43 when the hammer is retracted, and will drop into the shoe channel 45 and will come to rest against the floor.

The hammer used in the machine for driving the nails comprises a heavy, tubular body portion 50 that is telescopically slidable on the upper end portion of the hammer guide tube 41b. Fixed in the upper end of the body 50, as best shown in Fig. 8, is a nail driving rod or plunger 52 that is slidably contained in the bore 43. At its lower end, the rod 52 has a portion of reduced diameter, designated at 52a, set off by a downwardly facing tapered shoulder 53. The reduced portion 52a is adapted to enter the shoe stem channel to engage the nail head for driving the nail. The shoulder 53 will engage the flared upper end portion of channel 44 of the shoe to limit the downward travel of the hammer.

By reason of the fact that the shoe 42 always rides on the floor surface, and the provision of the conically tapered seat 46' in the upper end of the channel 46 on the stem 45 of the shoe, and the limiting of the downward drive of the hammer by the shoulder 53 of rod 52 engaging in the seat 46', the nails will all be uniformly driven and their heads equally set below the surface of the board.

The driving force of the hammer is effected by a pair of coiled springs 55 and 55 that have their lower end hooks attached to pins 56 extended from the opposite sides of the block 41a and which have upper end hooks attached to lugs 57 on the under side of a crosshead member 58 on the body 50 as shown in Fig. 1. The hammer is lifted against the tension of these springs through the mediacy of the lever arm 28 incident to its rotation by shaft 27.

By reference to Fig. 12, it will be observed that the cross head portion 58 of the hammer body 50 has vertical keys 60 at one edge thereof that are slidably contained in vertical keyways 61 formed in a bracket 62 that is fixed to the forward face of the gear box 16. This sliding con-

nection retains the hammer against rotation on its guide member as it moves up or down.

It is also to be noted, in Fig. 6, that the cross-head 58 has a flat horizontal under surface 58' extending in a front to rear direction relative to the travel of the machine and offset inwardly from the hammer axis.

On the outer end of the crank arm 28, that is fixed to the driven shaft 27, is a roller 63 that, during each rotation of the crank arm 28, engages the surface 58' and effects the lifting of the hammer body, thus to place the springs 55 under tension. In Fig. 6, the position of the roller at the time when it first engages with the crosshead to lift the hammer, is designated by the dotted circle 63a. The upward swing of the crank arm, then lifts the hammer. The direction of rotation is indicated by the arrow in Fig. 6.

When the lever arm has rotated to that position at which the roller 63 reaches the position indicated by the dotted circle 63b in Fig. 6, the hammer is then fully lifted and farther travel of the lever arm allows the roller to pass from the surface 58' to release the hammer. The springs 55 then actuate the hammer downwardly, causing its lower, diametrically reduced end portion 52a to enter the shoe channel to strike and drive the nail that has been admitted while the hammer was raised. The position of the hammer in its lowered driving position is shown in Fig. 6, and the nail head is seen as being set below the floor surface. In Fig. 8, the hammer is seen in a raised position.

The nail driving operation, in each instance, takes place while the machine is at rest. However, before the driving of each nail, the machine is advanced its proper interval for spacing the nails in a row. By reference to Fig. 6, it will be understood that when nails are driven close to the opposite edges of each board, the advance movements for such nailing would necessarily be alternately "short" and "long." The "short" distances would be about one-half inch. The "long" distances would be equal to the width of the board less the short distance. Due to this variation in distances, provision has been made herein for an automatic control of the advance movements to take care of this requirement that alternate advance movements be "long" and "short." This mechanism will now be described.

Mounted on the end of the roller 12 is a ratchet, ball clutch disk 70. This is revoluble axially of the roller trunnion and with each rotative movement thereof in a forward direction; that is, clockwise in Fig. 6, the roller 12 is rotated accordingly to advance the machine. A link 71 has one end thereof pivotally connected to the disk, eccentrically thereof, as at 72, and has its other end pivotally connected, by pivot bolt 73, to a lever arm 74. The arm 74 lies along one edge of the base 10 and has one end pivotally fixed thereto as at 75, and at its other end is operatively connected by means of an upwardly directed rod 76 and a guide block 77 with the lever arm 28. The rod 76 slides through a hole 77' in the guide block, and at its upper end has a nut 78 applied thereto to limit the extent of this sliding movement and to effect a holding connection through which the lever arm 74 can be actuated by the crank arm 28.

With each rotation of the shaft 27 and the crank arm 28, the connecting rod 76 will cause an oscillating movement of the lever arm 74; for example, moving it from the full line position

in which it is shown in Fig. 6, to the substantially vertical dotted line position, designated at 74b. With the swinging of the lever 74 through this arc, the link 71 causes a rotative advancement of the ratchet disk 70 that turns the roller 12 accordingly, and moves the machine forwardly a definite distance. In this instance, it is the interval for "long" spacing. It will be understood that this advance movement takes place while the hammer is being raised and is completed just before the hammer is released by the passing of roller 63 from the surface 58'. To bring about the "short" interval of advancement, alternately with the "long" intervals, I have provided the following mechanism.

With each upward swing of the lever arm 74 through the arc which has been designated by the double pointed arrow *a* in Fig. 6, a spring pressed pawl 80, pivoted on the lever 74, engages with a tooth or point of a four-pointed star wheel 81 that is rotatably supported on a side surface of the base 10 as shown in Figs. 1 and 6. This contact will advance the star wheel one-quarter turn. Fixed to the star wheel, to turn therewith, is a cam 82 with equally extending rises 82' at diametrically opposite sides thereof. Rotatably mounted along that same edge of the base 10, on which the star wheel is located, in bearings 83 and 83', is a horizontal shaft 84 having a laterally turned end portion 85 that is so located and so extends that it may be engaged by the parts 82' of the cam in its rotative advancement. A stop arm 86 extends radially from the shaft 84 in the same plane as the part 85. The cam 82 is so related to the shaft 84 that when a part 82' thereof is rotated into contact with the laterally turned shaft end 85, it rotates the shaft 84 to a position at which the stop arm 86 will extend upwardly, as in Fig. 6 and, at such position, will be out of the plane of travel of the lever arm 74. When the lever arm 74 swings upwardly from its full line position in Fig. 6, and the pawl 80 engages the star wheel to advance the cam to disengage the part 85, the shaft 84 will then be allowed to rotate back and the stop arm 86 swings therewith to a substantially horizontal position at which it extends in the path of return travel of lever arm 74, so that it will then act to prevent the complete return movement of this lever arm to that position shown in dotted lines 74c in Fig. 6. This limits the full return of the ratchet clutch disk 70 accordingly and shortens the arc of travel of lever 74 so that the next advance movement of the machine will be only that made possible by the travel of the lever arm 74 through the arc indicated by the double pointed arrow *b* shown in Fig. 6. This results in the "short" interval of advancement of the machine. By reason of the cam action, alternate advance movements will be long and short.

To vary or change the "long" interval of advancement, the point of attachment of the link 71 with the lever arm 74 may be changed closer to or farther from the pivot point 75; this being possible due to the fact that bolt 73 is held in a slot that is longitudinally of the lever 74 and may be adjusted therewith. Or the extent of return of the lever 74 may be changed by the setting of a stop 87 in a horizontal slot 88 in a plate 89 fixed to the base 10.

To vary the "short" interval of advance, the arm 86 may be adjusted to different positions along the shaft 84 so that the return travel of the lever arm 74 controlled thereby may be made more or less. For holding any adjustment of the

arm 86, it is provided with a set screw 86' that may be tightened against its mounting shaft. A small coiled spring 84 is applied about shaft 84 and is attached at one end to the base and at its other end to the shaft to urge it rotatably in a direction to cause the part 85 to lie in the path of cam 82.

The ratchet clutch mechanism connecting the disk 70 with the roller 12 is illustrated best in Fig. 7 wherein it is seen that disk 70 is rotatably on the end hub 90 of roller 12 and has a one-way driving connection with the hub effected through the mediacy of a ball clutch mechanism of common type herein designated at 92.

The roller 12 is equipped with a friction brake mechanism designated at 93 that prevents free turning of the roller and overcomes any tendency of the machine to roll after an advance movement has been completed.

The operation of the nail picker mechanism, shown in Figs. 4 and 5, is synchronized with the advance movement of the machine so that immediately following each nail driving action of the hammer, a nail is discharged from the channel 38 into the nail delivery tube 40. The nail moves by gravity in the tube to the block 41a, and when the hammer is lifted, it drops into the channel 43 of the block and from there passes into the mounting stem of the shoe 42. The row of nails supplied from the hopper and held in the guide channel 38 feeds downwardly as the nails are successively removed from the lower end of the channel and the channel is kept filled by the picker arm.

In Fig. 4, it is shown that the end of the channel 38 is closed by a cross slide 100 carried in a bearing 101 that is formed as part of a block 102 fixed to the lower end guide bar 39 as noted in Fig. 4. Located about one end of the slide is a coil spring 103 held under compression and engaged at one end against the adjacent bearing 101 and at its other end against a washer 104 fixed to the shaft end by screw 105. The spring yieldingly retains the slide in its retracted position at which a notch 106, formed in a side surface of the slide, as noted in Fig. 4, registers with the lower end of the nail channel 138. The notch is of such depth that it will contain one nail only at a time therein. To discharge the nail from the notch to the delivery tube 40, the slide is actuated endwise to a distance that will move the notch into registration with a downwardly tapered pocket 107 formed in a block 108 that is fixed to the inner face of the bracket 62. The nail delivery tube 40, as noted in Fig. 8, connects with the lower end of this pocket and leads therefrom to the hammer guide 41a. A finger 109 is fixed to the channel side bar 39 and this extends into the path of travel of the nail head when the slide is actuated endwise, thus to cause the nail to be moved out of the notch 106 and dropped into the pocket 107.

The means for actuating the slide 100 in proper timing with the machine operations is shown in Figs. 1, 16, 14 and 15. Here it is shown that a lever 115 is pivotally mounted as at 116 by a bracket 117 attached to a side wall of gear box 16. One end of the lever has an operating connection, as seen in Figs. 4 and 5 at 119, with the slide 100. The other end of the lever is curved to an extent that it will lie in the path of travel of the crank arm 28 as it swings across the top of its arc of travel, and will be engaged by the arm just after the hammer has been dropped, and so actuated thereby as to shift the slide 100 endwise and drop

a nail into the tube 40. When lever 115 is disengaged by the crank arm, the slide is returned by spring 103 to position for receiving another nail into notch 106.

5 The driving clutch mechanism that connects the motor shaft 21 with the drive shaft 22, as seen in Fig. 11, comprises a friction cone 120 fixed on the motor shaft and a complementary friction head 125 keyed on the drive shaft. The friction head is adapted to be shifted up and down on the shaft 22 to engage or disengage the friction cone, and this is here accomplished by a lever 126 having one end pivoted to the bracket 15 as at 127 in Fig. 3, and having a ball bearing connection 130 with the hub portion of the friction head through which the latter may be held in driving contact with the cone.

To hold the clutch set, a latch lever 140, pivoted at its upper end on a bracket 141 attached to box 16, depends across the free end of lever 126. This latch lever has a notch 142 (Fig 1) in which a stud 143 on the lever may be seated to hold the clutch engaged. To release the drive, the latch is disengaged and a spring 145, attached to lever 126 and to the bracket 141, lifts the clutch friction head free of the driving cone.

In order that the machine may be automatically stopped after advancing across an area, I provide a horizontal push rod 150, guided slidably 20 in a guide block 155 at the forward side of the machine, and attached pivotally at its other end to the latch lever 140. At the forward end of the rod is a knob 152 designed to engage with a wall or abutment to disengage the latch, thus to automatically stop the operation when a room has 25 been traversed.

In order that the machine, when not being used, may be rolled freely on a floor, I provide a supporting carriage 160 therefor, equipped with corner casters 16. This carriage is mounted on the underside of base 10 between the rollers 11 and 12, and it has longitudinal inclined side rails 163 engaged with similarly inclined rails 164 formed on a frame 165 that is applied to the under side of the base frame 10. The carriage 160 is held by vertical bolts 166 against longitudinal movement relative to base 10, but may raise or lower on the bolts. Springs 167 applied about the lower ends of the bolts, urge the carriage to raised position. The frame 165 is longitudinally adjustable relative to the base and, by this movement, will cause the caster frame to be pushed downward from the base to lift the machine.

The shifting of the frame 165 is effected by 55 means of a hand lever 170 fixed on a shaft 171 that is rotatably mounted just forward of bracket 15 to extend down through the base 10. At its lower end, the shaft 171 has a crank pin 172 fixed thereon to engage the frame 165 in a manner whereby the turning of the shaft will shift it in one direction or the other as required to raise or lower the machine; this being due to the location of the inclined rails 163 and 174 provided respectively on the carriage and frame.

60 Having thus described my invention, what I claim as new therein and desire to secure by Letters Patent is—

1. A floor nailing machine comprising a base, 65 rollers supporting said base for its straight line travel across a floor, a motor on the base, a shaft continuously driven by the motor, a clutch operable by the driven shaft to drive one of the rollers to cause intermittent advance movements of the base across a floor and means to cause the clutch to effect movements of alternate short

and long intervals of definite length, nail driving means on the base, and devices operated by said driven shaft to effect a nail driving operation following each advance movement of the base.

2. A floor nailing machine comprising a base, rollers supporting said base for straight line travel across a floor, a motor on the base, a shaft continuously driven by the motor, a crank arm rotated by the shaft, a one-way clutch disk associated with one of the rollers, and linkage actuated by said crank arm and connected with said disk to effect oscillating action thereof whereby the roller is caused to intermittently advance the base across a floor, nail driving devices on the base, and actuated by the crank arm in timing with the advance movements of the base to drive a nail into the floor after each advance movement thereof.

3. A floor nailing machine comprising a base, rollers supporting said base for straight line travel across a floor, a motor on the base, a shaft continuously driven by the motor, a lever pivoted on the base, and means connecting said lever with the driven shaft to cause the lever to be oscillated in a forward and reverse direction and in accordance with rotation of the shaft, a one-way driving clutch associated with one of the rollers, a link connecting the oscillating lever and clutch for the actuation of the latter to effect a definite advance movement of the machine across the floor to be nailed, with each advance swing of the lever, a nail driving device on the base and operated under control of the rotating shaft and in timing with the advance movements of the base.

4. A floor nailing machine as recited in claim 3 wherein means is operatively associated with said pivoted lever and actuated thereby to shorten alternate return movements of the oscillating lever, thus to shorten alternate advance movements of the machine accordingly.

5. A floor nailing machine comprising a base, rollers supporting said base for straight line travel across a floor, a motor on the base, a shaft adapted to be continuously driven by the motor, a lever arm pivoted on the base for oscillation, a crank arm on the shaft, a link operatively connecting the crank arm and lever to actuate the

latter with forward and return oscillating action, a one-way driving clutch device associated with one of the rollers, a link operatively connecting the oscillating lever and clutch device for effecting advance movements of the machine with the forward swinging actions of the lever, a movable stop device mounted on the base and adapted to be engaged with the lever to shorten its normal return travel, and a stop control mechanism

- 5 that is actuated by the successive oscillations of the lever to move the stop device into and from functional position to shorten alternate return movements of the lever, thereby to effect the shortening of alternate advance movements of the machine as effected through the clutch device.
- 10
- 15

6. A nail driving machine comprising a base frame, rollers mounting said base for straight line travel across a floor, a rotatably driven shaft on the base frame, a hammer guide, a spring loaded hammer mounted thereon, a nail holding means associated with the hammer guide, nail delivery means for the feeding of nails to said nail holding means, an over-running clutch associated with one of said rollers, a crank arm fixed to the said shaft, and devices operated by the crank arm during each rotation thereof to actuate the clutch to effect a definite advance movement of the machine, means actuated by the crank to lift the hammer, means to release a nail to the holding means, and means to release the hammer to cause said nail to be driven.
